UNITED STATES PATENT OFFICE

153,590

DESIGN FOR AN AIRPLANE

Ellis V. Eichman, Brownsville, Tex.

Application December 5, 1947, Serial No. 142,962

Term of patent 14 years

(Cl. D71--1)

To all whom it may concern:

Be it known that I, Ellis V. Eichman, a citizen of the United States, residing at Brownsville, in the county of Cameron and State of Texas, have invented a new, original, and ornamental Design for an Airplane, of which the following is a specification, reference being had to the accompanying drawing, forming part thereof.

Figure 1 is a top plan view of an airplane, showing my new design,

Figure 2 is a front elevational view thereof,

Figure 3 is a side elevational view, and

Figure 4 is a top perspective view of the same.

I claim:

The ornamental design for an airplane, as shown.

ELLIS V. EICHMAN.
